PORTABLE PHONOGRAPH

Harry J. Brown, Wilmette, Ill., assignor to Strombecker Corporation, Chicago, Ill., a corporation of Illinois

Filed Sept. 25, 1964, Ser. No. 81,869

Term of patent 14 years

(Cl. D56—4)

FIG. 1 is a perspective view of a portable phonograph embodying my new design;

FIG. 2 is a front elevational view thereof;

FIG. 3 is a side elevational view thereof;

FIG. 4 is a fragmentary sectional view taken on the plane of line 4—4 in FIG. 1 and viewed in the direction indicated;

FIG. 5 is a fragmentary sectional view taken on the plane of line 5—5 in FIG. 1 and viewed in the direction indicated.

The rear of the portable phonograph is substantially the same as the front and the side not shown is substantially the same as the side shown.

I claim:

The ornamental design for a portable phonograph, substantially as shown and described.
